UNITED STATES PATENT OFFICE.

GEORGE LANTEN ROTHARMEL, OF SUNBURY, AND CHARLES HENRY DODGE, OF NORTHUMBERLAND, PENNSYLVANIA.

DESIGN FOR A GAME-BOARD.

SPECIFICATION forming part of Design No. 29,082, dated July 19, 1898.

Application filed June 25, 1898. Serial No. 684,509. Term of patent 3½ years.

To all whom it may concern:

Be it known that we, GEORGE LANTEN ROTHARMEL, residing at Sunbury, and CHARLES HENRY DODGE, residing at Northumberland, 5 in the county of Northumberland and State of Pennsylvania, citizens of the United States, have invented and produced a new and original Design for a Game-Board, of which the following is a specification.

10 This invention relates to a new and original design for a game-board, and it has for its object to provide a design of this character that shall be both useful and ornamental.

15 The leading feature of the design resides in a game-board body having on the upper face thereof a central rectangular field bounded at two sides by parallel oppositely-located staves of music having therein scales of notes, the oppositely-located staves being reversely 20 disposed to each other and respectively provided with the treble and bass clef signs.

25 A minor feature of the design resides in the game-board body having a rectangular shape and provided on its upper face with oppositely-located rectangular marginal spaces bounding two sides of the central rectangular field.

30 In the drawings, Figure 1 is a plan view of a game-board embodying the herein-described design. Fig. 2 is a cross-sectional view of the same.

Referring to the accompanying drawings, the numeral 1 designates a game-board body of a rectangular form and provided on the upper face thereof with a central rectangular field 2. This rectangular field is bounded at two of its sides by the parallel oppositely-located rectangular marginal spaces 3, which extend the full width of the game-board surface. The remaining sides of said central rectangular field 2 are bounded by the oppositely-located parallel staves of music 4 and 5. These staves of music have their lines arranged at right angles to the marginal spaces 3 and are provided with running scales of 45 notes. The said staves 4 and 5 are reversely disposed to each other and are respectively provided at one end thereof with the treble and bass clef signs.

What is claimed is—

50 The design for a game-board herein shown and described.

In testimony that we claim the foregoing as our own we have hereto affixed our signatures in the presence of two witnesses.

GEORGE LANTEN ROTHARMEL.
CHARLES HENRY DODGE.
